Chas Ingraham
Design for block fronts
Patented Dec 22 1857

Elias Ingraham of Bristol Conn.
Letters Patent No. 970. Dated Dec. 22. 1857.

The schedule referred to in these Letters Patent and making part of the same.

To all whom it may concern:

Be it known, That I Elias Ingraham of the Town of Bristol County of Hartford and State of Connecticut have invented or introduced a new and original design, for the front dashes of blocks and time pieces, and I do hereby declare that the following is a correct description of the same, reference being had to the accompanying drawing and to the letters of reference marked thereon.

The nature of my invention consists in the construction of the dash for clock and other fronts, with a double circle, with rosettes and frames.

To enable others to make and use my invention I will proceed to describe the same.

The Drawing.

Fig. 1 a view of the front.

Fig. 2 back view showing how it is joined together.

Fig. 3 end D. Section part. D. L.

The material composing the dash is of wood of the suitable kind and hung in the usual manner.

The top and bottom parts are turned circles A & B, and are fastened together by means of a cross piece, C, part of each dash being rabbed out to fit, and glued to the cross piece.

The rosettes D are fitted and fastened in the same way to the cross piece C, and circles A & B.

The frame of the circle B is cut out of the inner plain wood face of the opening for the view of the pendulum, and fits in the rabbet of the circle B, being a saving of time and material. The rosette E is painted on the panel as shown in the drawing Fig. 1.

What I claim as my design or production and desire

2

Des. 970

to secure by Letters Patent, is The design for Clock or Time-piece front-sashes, with two circular parts A & B, and the rosettes D & E, in the manner and for the purpose, substantially as herein set forth and described
